UNITED STATES PATENT OFFICE.

GEORGE ALBERT WILLIAMS, OF LARK, UTAH.

MIXER.

1,230,638.

Specification of Letters Patent. Patented June 19, 1917.

Application filed May 23, 1916. Serial No. 99,387.

To all whom it may concern:

Be it known that I, GEORGE A. WILLIAMS, a citizen of the United States, residing at Lark, in the county of Salt Lake and State 5 of Utah, have invented new and useful Improvements in Mixers, of which the following is a specification.

This invention relates to improvements in mixers primarily designed for use in the agitation of ore, water and oil in the separation of values from the ore by what is commonly known as the bubble flotation process, but which also may be employed for other 10 analogous purposes to effect the thorough agitation and aeration of substances to be subjected to separatory treatment.

The object of the invention is to provide a mixer or agitator whereby the particles of the ore may be agitated with the water and 15 oil to effect a more thorough division of the solid matter to be treated, the more thorough diffusion of the bubbles of oil throughout the water and a more efficient modification of the physical properties of the water so 20 that bubbles of the proper kind may be formed, and which in addition will also aerate the mass under treatment to effect a more reliable and efficient coating of the values with a film of oil and more efficient adhesion of the particles of values to the walls 25 of the bubbles.

The invention consists of the features of construction, combination and arrangement of parts hereinafter fully described and 30 claimed, reference being had to the accompanying drawings in which:—

Figure 1 is a vertical section through an agitator or mixer constructed in accordance with my invention.

Fig. 2 is a top plan view of the mixer, the mixer shaft appearing in section.

Figs. 3 and 4 are sections on the lines 3—3 and 4—4 of Fig. 1.

Fig. 5 is a sectional view of one of the 45 screens.

Fig. 6 is a fragmentary sectional view through the mixing tank showing a portion of one of the air nozzles.

Referring to the drawings, 1 designates 50 the mixer as a whole, which comprises an outer primary separating tank or vessel 2 and an inner mixing tank or vessel 3. These tanks or vessels are coaxially arranged and spaced to provide an intervening annular 55 combined separating chamber and feed passage 4, and said tanks or vessels are respec-

tively provided with conical lower ends 5 and 6 having outlets 7 and 8 provided with controlling valves 7' and 8'. The tank 2 has connected therewith feed pipes 9 provided 60 with controlling valves 9' and which connect therewith at the same or different levels, for the supply of the material to be treated to the chamber or passage 4. This material may consist of a mineral bearing 65 ore, together with a carrier vehicle, such as water and oil of proper specific gravity, the pulp being fed to the hopper preferably from an elevated source and through the force of gravity. In practice it will be understood 70 that the ore as it comes from the mine is combined with a suitable proportion of water, the mixture ordinarily consisting of from 15% to 20% solids and the greater part 75 of the remainder water, a certain amount of the specified oil or oils being added thereto prior to separation, say in the proportion of 1 to 3 pounds of oil to a short ton of crude ore containing, for example, 1% copper. This oil is added to the mixture which is feeding 80 to the primary separator drop by drop or in suitably divided quantities, so that, as a result of the agitation hereinafter described, the oil will be thoroughly diffused throughout the ore and subdivided for the production 85 of bubbles and a modification of the physical properties of the water for the production of bubbles of the proper kind.

The valve 8' in the bottom of the hopper is normally closed, and the hopper bottom is 90 filled with the water, as shown at 10, up to a desired water level line $x-x$, which body of water forms a support for the flotation body 10' of oil and water which reaches up to the level of the top of the mixing tank. The arrangement is thus such that the oil coated 95 particles of ore and other materials of less specific gravity than body 10' will float upwardly therethrough, the fine refuse being also carried up with the oil and passing with 100 the oil from the top of the hopper chamber into the top of the mixer, while the heavy particles of ore which are of greater specific gravity than the water will pass downward into the bottom of the separator tank for 105 subsequent discharge. In this manner all the small particles of material, such as will pass through a 60 mesh screen, and which can be treated, will be separated from the coarser particles which cannot pass through 110 a screen of the character mentioned and which therefore cannot be treated, and such

coarser particles of the material will be discharged as refuse, while values will be carried forward, together with any fine foreign substances which cannot be preliminarily separated therefrom, for a mixing action and a final separatory action in consecutive order.

The pulp matter feeding into the mixer is subjected to a mixing action through a novel construction of mixing mechanism, which I will not proceed to describe. Arranged within the tank 2 are conical aprons or deflectors 11 suitably secured to the tank 2 and projecting downwardly and inwardly at an angle of about 45° to a point radially about midway between the wall of the tank and the axial center thereof. These aprons or deflectors are disposed at different heights or levels and are adapted for coöperation with vertically disposed screens 12 arranged beneath the respective deflectors and between adjacent deflectors and in spaced relation to the walls of the tank to provide liquid passages 13. The screens consist, preferably, of sheet metal plates having perforations of a suitable degree of fineness therein for the flow of liquid from the center of the tank into the passages 13 and drainage of the liquid back again into the body of the tank through the lower ends of said passages.

Extending vertically and axially within the mixing tank is a shaft 14 journaled in suitable bearings 15 and provided with a pulley 16 whereby motion may be communicated thereto from a suitable source of power. The shaft is designed in practice to be rotated at a given or desired speed, and is provided at different elevations or levels with radial mixing blades 17, arranged in superposed sets corresponding to the levels of the screens, one set for coöperation with the deflector or deflectors at a certain level and the screens at the next adjacent lower level. The mixer blades rotate in paths at right angles to the direction of flow of the material, which is designed to flow by gravity through the mixing chamber to the feed outlet 7, and such blades operate on the passage of the pulp to thoroughly agitate and stir the same and diffuse the oil throughout the mass and to otherwise put the ingredients of the pulp in condition for an efficient and reliable final separation. The blades also force the oil through the perforations in the screen and into the passages 13, the oil draining back into the mixing chamber, whereby the oil globules will be broken up and the oil placed in a more limpid or finely divided condition to adapt it to penetrate every portion of the solid mass of the pulp and to effect the coating of the ore particles in a more efficient manner. It will thus be understood that the pulp flowing upward through the primary separator to the mixer will first be separated from the coarsest particles of the

ore which will descend into the bottom of the hopper tank for discharge, while the finer mineral bearing particles of ore will pass upward through and with the oil and enter the mixing chamber, through which it will feed downward by gravity while being thoroughly agitated and mixed with the oil, the resultant mixture passing through the outlet 7 to a suitable separator for further treatment. Disposed within the lower portion of the hopper is an annular air cell or chamber 19, preferably of triangular form, said cell being preferably formed of a back and bottom of sheet metal or other impervious material and a front of canvas or other sufficiently porous material. This cell or air supplying nozzle is designed for the supply of streams or divided portions of air to the passage 4 to combine with the oil, the bubbles of oil and air gathering or collecting in the form of a frothy mass, carrying with it all of the particles of ore of available size, such frothy mass floating upward and discharging into the top of the mixing vessel. By this action of injecting air into the pulp, the oil will be further subdivided and aerated, thus further decreasing the specific gravity of the oil and further increasing its supporting area, so that a less quantity of oil will be required for separating any given amount of material, and consequently the cost of oil supply and recovery will be correspondingly reduced. Furthermore, the action of the air in increasing the buoyancy and supporting capacity of the oil insures the separation from the refuse of particles of ore of maximum weight within the screening limit, thus preventing any loss of ore which would be liable to occur under ordinary conditions.

I claim:—

1. In an agitator or mixer, the combination of an external receptacle adapted to contain a body of liquid to a determined level, an inner receptacle in communication at its upper portion with the upper portion of the outer receptacle, said inner receptacle being spaced from said outer receptacle, agitating means within the inner receptacle, aerating means within the outer receptacle, and a discharge outlet at the bottom of said inner receptacle.

2. An agitator or mixer of the character described comprising an outer receptacle adapted to contain a body of liquid in its lower portion to a predetermined level, an inner receptacle disposed within said outer receptacle and in spaced relation thereto, said inner receptacle being in communication at its top with the top of the outer receptacle, the space between said receptacles above the body of liquid forming a passage for the upflow of the material under treatment by flotation action, agitating means within the inner receptacles, and means

within the outer receptacle above the level of the body of liquid for discharging streams of air into said passage.

3. A mixer or agitator of the character described comprising an outer receptacle having a lower receiving space for a supporting body of liquid, an inner receptacle in spaced relation thereto to provide an intervening passage communicating with the upper portion of said inner receptacle, said passage being adapted to contain a body of oil and water of less specific gravity than said supporting body of liquid agitating means within the inner receptacle, an outlet from the bottom of said inner receptacle, and aerating means within said receptacles.

4. A mixer or agitator of the character described comprising an outer receptacle having a lower containing space for a supporting body of liquid, an inner receptacle arranged within the outer receptacle in spaced relation thereto to provide an intervening flow passage adapted to contain a flotation body of oil and water and communicating at its top with the top of the inner receptacle, a series of superposed deflectors disposed within the inner receptacle, an outlet from the bottom of said inner receptacle, and a series of rotary agitators arranged within the inner receptacle beneath the respective deflectors.

5. A mixer or agitator of the character described comprising an outer receptacle having a receiving space at its bottom for a supporting body of liquid, an inner recep-

tacle arranged within the outer receptacle in spaced relation thereto and forming an intervening passage for the reception of a flotation body of oil and water, said passage communicating at its upper end with the top of said inner receptacle, agitators arranged at different levels within said inner receptacle, a discharge outlet at the bottom of the inner receptacle, and conical deflectors within the inner receptacle above the respective agitators.

6. An agitator or mixer of the character described comprising an outer receptacle having a containing space at the bottom thereof for a body of supporting liquid, an inner receptacle arranged within the outer receptacle and in spaced relation thereto to provide an intervening flow passage to contain a flotation body of oil and water, said passage communicating at its upper end with the upper end of the inner receptacle, a discharge outlet at the bottom of the inner receptacle, screen bodies at different levels within the inner receptacle disposed concentric with and spaced from the side walls thereof, rotary agitators arranged in the spaces bounded by said screens, and conical deflectors arranged to overhang said rotary agitators.

In testimony whereof I affix my signature in presence of two witnesses.

GEORGE ALBERT WILLIAMS.
